UNITED STATES PATENT OFFICE.

CHARLES B. JACOBS, OF BLOOMFIELD, NEW JERSEY, ASSIGNOR, BY MESNE ASSIGNMENTS, TO AIR REDUCTION COMPANY, INCORPORATED, A CORPORATION OF NEW YORK.

PROCESS FOR THE PRODUCTION OF ALKALI-METAL CYANIDS.

1,324,119.

Specification of Letters Patent.

Patented Dec. 9, 1919.

Application filed December 19, 1916. Serial No. 137,809.

To all whom it may concern:

Be it known that I, CHARLES B. JACOBS, a citizen of the United States, residing at Bloomfield, in the county of Essex and State of New Jersey, have invented certain new and useful Improvements in Processes for the Production of Alkali-Metal Cyanid, of which the following is a full, clear, and exact description, such as will enable others skilled in the art to which it appertains to make and use the same.

This invention relates to processes for the production of nitrogen compounds, and with respect to its more specific features, to 15 a process for the production of alkali metal cyanids.

One of the objects of the invention is the provision of a practical process by means of which may be effected the direct combination of free, or elementary, nitrogen with 20 alkali metal compounds to form cyanids.

Another object of the invention is the provision of a practical process for effecting the direct combination of free nitrogen 25 with alkali metal compounds to form cyanids.

Other objects will be in part obvious and in part pointed out hereinafter.

The invention accordingly consists in the 30 several steps and the relation and order of one or more of such steps with relation to each of the others thereof, which will be exemplified in the hereinafter disclosed process, and the scope of the application of 35 which will be indicated in the claims that follow.

It is well known that the inert character 40 of free, or elementary, nitrogen has heretofore prevented its direct combination with other elements, except in meager traces, without the influence of catalytic agents, or the electric spark, or silent discharge, or the electric arc. Heretofore to effect combination of nitrogen with the alkali metals to 45 form cyanids or intermediate compounds, from which alkali cyanids may be formed, it has been necessary to use some compound of nitrogen which will break up at the reacting temperature, and furnish nitrogen in 50 a nascent state.

By means of the present process alkali metal compounds may be effectively treated with nitrogen to produce different compounds of nitrogen, and further, metal com-

pounds may be prepared or placed in such 55 chemical or physical condition as will be most suitable for treatment with nitrogen.

While any of the alkali metal compounds may be treated in accordance with the present process so as to produce the related 60 cyanids, as a practical illustration, the invention is herein disclosed in connection with the production of sodium cyanid from sodium carbonate, this latter furnishing a cheap and readily available compound for 65 the purpose.

In accordance with this invention it has been found that if an alkali compound be heated with nitrogen in the presence of a carbid of an alkaline earth, that an interaction will take place resulting in the production of a cyanid of the alkali. For example, if calcium carbid be heated with the carbonate or chlorid of sodium or of potassium in a dry state to the point of fusion of 70 the alkali compound, and nitrogen forced therethrough, the carbonate or chlorid is converted into the cyanid. The presence of free carbon in the mass at the time the nitrogen is forced therethrough is very beneficial if not essential to the formation of the cyanid on a commercial scale. The free carbon referred to is in excess of that normally present in the carbid, which is not sufficient 75 for the purposes of the reaction.

The reaction which probably takes place 80 may be expressed by the equations:

All of these reactions are exothermic, so that when the reaction starts sufficient heat will under proper conditions be generated by the reaction to continue the reaction. In 100 such case it is only necessary to maintain the reaction temperature until the reaction is complete, either by heat insulation of the furnace in which the reaction is taking place, or otherwise.

In carrying out this process, proper proportions of dry alkali compound, as for example the carbonate or chlorid of sodium

105

or potassium and carbid of the alkaline earth, as for example, calcium, are heated with a suitable amount of charcoal until fusion takes place. Nitrogen or a gas containing nitrogen is then forced through the fused mass, preferably under pressure, and the temperature brought to the point where the reaction starts. This in case the sodium carbonate is used is about 1098° C., and in case the sodium chloride is used is about 820° C. The nitrogen is then forced through the mass until the reaction is complete.

A practical illustration of the carrying out of this process in connection with the apparatus illustrated in the accompanying drawings, which is a vertical central section through the device, is as follows: A charge consisting of the proper relative amounts, of the alkaline earth carbid, and of the alkali compound, is mixed with a suitable amount of free carbon, preferably in the form of charcoal and placed in a retort 1 of a furnace 2. In case the charge is to consist of the sodium carbonate and commercial calcium carbid the relative amounts would be approximately 106 pounds of the carbonate, 80 pounds of the carbid containing approximately 85% CaC_2 , and 12 pounds of charcoal; while if the chloride of sodium were used there would be required of it 118 pounds.

The retort 1 containing the charge is then heated until the charge is fused, which may be done by gas burners 3, in a combustion chamber 4. The walls of the furnace 2 are preferably heat insulated. The temperature of the charge may be regulable in accordance with the readings of a suitable pyrometer as indicated at 5.

When the mass is fused, nitrogen, or a gas containing nitrogen, as for example air from which the oxygen has been removed, is admitted, preferably under pressure, as for example through an opening in the bottom of the retort, leading from a nitrogen containing tank 7, and forced up through the fused mass. The pressure may be determined by suitable gages as 8.

The reaction temperature is now maintained as indicated on the pyrometer, which,

due to the heat generated by the reaction, will not require the supplying of much if any external heat, and nitrogen is continually supplied until a drop in temperature as indicated on the pyrometer indicates that the reaction has been completed.

The finished charge, containing the alkali cyanid and the other reaction products, together with some of the original ingredients of the charge which remain unconverted, may now be removed from the furnace, as through a swinging bottom 9 of the retort, and allowed to cool. If it is desired to separate the cyanid from the other constituents of the charge this may be done by any suitable process.

As many changes could be made in carrying out the above process without departing from the scope of the invention, it is intended that all matter contained in the above description shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:—

1. The process of producing alkali metal cyanid which comprises, heating a mixture of an alkaline earth carbid with carbon, in excess of that normally present in such carbid, and an alkali metal compound and causing nitrogen to react with the heated mass.

2. The process of producing sodium cyanid which comprises, heating a mixture of calcium carbid with carbon, in excess of that normally present in such carbid, and sodium carbonate and causing nitrogen to react with the heated mass.

In testimony whereof I affix my signature in the presence of two witnesses.

CHARLES B. JACOBS.
